No. 12,091

JANUARY 4, 1881

Cut 235.

UNITED STATES PATENT OFFICE.

H. CLAY BASCOM, FRANCIS RITCHIE, AND CYRUS A. HODGES, OF TROY,
NEW YORK, ASSIGNEES TO THE N. S. VEDDER PATTERN WORKS, BASCOM,
GALBRAITH & CO., OF SAME PLACE.

DESIGN FOR A STOVE.

SPECIFICATION forming part of Design No. 12,091, dated January 4, 1881.

Application filed November 24, 1880. Term of patent 3½ years.

To all whom it may concern:

Be it known that we, H. CLAY BASCOM, FRANCIS RITCHIE, and CYRUS A. HODGES, each of the city of Troy, in the county of Rensselaer and State of New York, have jointly invented a new and original ornamental Design for Cooking-Stoves, of which the following is a specification, reference being had to the accompanying cut, print, or engraving of

10 a stove having our said new design.

The design of the compound panel ornament A consists of the raised quadrilateral surface b, having round corners, the peculiar compound ornament c c, extending diagonally 15 across the part b from one corner to the opposite one and upon the band d, and the two triangles e f g, having therein the compound stalk, leaf, and flower ornament h h' and the ornaments i i' at the angles, all shaped and 20 arranged together as represented in the accompanying print.

The design for the panel-border B consists of the outer ornamental molding, j, the corner ornaments k, and the side ornaments, l, each 25 composed of a fillet-border, l', with rounded ends and surrounding the row of oblong pointed ornaments l', the whole being shaped and combined as shown in the accompanying engraving.

30 The design for the doors C D consists of the compound panel ornament A and compound panel-border B, each composed as above specified, and both arranged together so as to present the combined appearance represented in 35 the accompanying cut.

The design for the door or panel E consists of the compound panel-border, composed of the parts m n o, and the central compound ornament, F, all shaped and arranged together 40 as shown in the aforesaid print.

The design for the front door, G, consists of the upper panel, H, having the two quadrilateral illumination-apertures p, with truncate corners, and the intermediate and lateral ornaments q, the lower projecting panel, I, hav-

ing the four draft-apertures r, with arched tops and intermediate and lateral ornaments s, and the middle panel, J, inclined to the panels H I, and having the oblong rectangular tablet t, all shaped and arranged together as represented in the aforesaid engraving.

The design for the legs consists of the central downwardly-pointing shield, K, composed of the ornamental border-molding u, having a straight top and convergently-curved sides, 55 central ornament, v, and outside pendent ornament, w, and the two ornamental flank-shields L L', each shaped and all combined as shown in the aforesaid cut.

What we claim as our invention is— 60

1. The design for the compound panel ornament A, composed of the parts b, c c, d, e f g, h h', and i i', all shaped and arranged together as set forth.

2. The design for the panel-border B, composed of the parts j k l l' l'', all shaped and arranged together as set forth. 65

3. The design for the doors C D, consisting of the compound panel ornament A and the compound panel-border B, each composed and 70 both combined as described and shown.

4. The design for the door or panel E, composed of the parts m, n, o, and F, all shaped and arranged together as set forth.

5. The design for the front door, G, composed 75 of the parts H p q, I r s, and J t, all shaped and arranged together as shown and described.

6. The design for the legs, consisting of the parts K u v w and L L', all shaped and combined as set forth. 80

In testimony whereof we hereunto set our hands, in the presence of two subscribing witnesses, this 22d day of November, 1880.

H. CLAY BASCOM.
FRANCIS RITCHIE.
CYRUS A. HODGES.

Witnesses:

JAMES A. GILMAN,
CHESTER BASCOM.
